UNITED STATES PATENT OFFICE.

ARTHUR G. HATCH, OF DULUTH, MINNESOTA.

CONCRETE BLOCK.

1,412,686.

Specification of Letters Patent. Patented Apr. 11, 1922.

Application filed January 12, 1921. Serial No. 436,638.

To all whom it may concern:

Be it known that I, ARTHUR G. HATCH, a citizen of the United States, residing at Duluth, in the county of St. Louis and State 5 of Minnesota, have invented certain new and useful Improvements in Concrete Blocks, of which the following is a specification.

This invention relates to a new and improved concrete block construction, and more 10 specifically to concrete blocks so designed that they may be utilized to form a completely bonded double wall without necessity for separate bonding elements.

In concrete wall construction heretofore 15 in use the walls have comprised blocks extending the full width of the wall or of two separate walls bonded by additional bonding elements. According to the present invention the wall is formed of two separate series 20 of oppositely faced blocks, the blocks being provided with flanges adapted to overlap so as to integrally bond the two face walls.

It is highly desirable in hollow blocks of 25 this character to utilize the full strength of the material in order to make them as light as possible and to minimize the amount of the block material necessary. To this end my invention also comprises the placing of metal reinforcements in the blocks.

30 While the interior air spaces in walls of this character serve as insulation, it is at times desirable to provide additional insulating means, and to this end my invention involves the formation integrally with the 35 block of an outer insulating surface. This surface may be formed of cinder concrete or other insulating compositions. These compositions mentioned have the additional feature of being adapted to receive nails, there- 40 by facilitating the attachment of finishing material to the wall.

It is an object of the present invention to provide a new and improved wall block adapted to form with uniform blocks a fully 45 bonded double wall.

It is a further object to provide a wall constructed in this manner in which fully isolated air spaces are provided.

It is an additional object to provide a block 50 which is reinforced to utilize the material to the best advantage and which is provided with insulating material forming an integral part thereof.

Other and further objects will appear as 55 the description proceeds.

I have illustrated the preferred embodiment

ment of my invention in the accompanying drawings, in which—

Figure 1 is a fragmentary perspective view showing a wall formed with one type 60 of blocks covered by my invention;

Figure 2 is a plan view of one of the blocks used in Figure 1;

Figure 3 is a view similar to Figure 1, showing another form of block; 65

Figure 4 is a plan view of one of the blocks of Figure 3;

Figure 5 is a face view of one of the blocks of Figure 3;

Figure 6 is a perspective showing still an- 70 other form of my block construction;

Figure 7 is a plan view of one of the blocks used in Figure 6;

Figure 8 is a face view of the block of 75 Figure 7;

Figure 9 is an end view of the block of Figure 7;

Figure 10 is a plan view of a further modified form of block;

Figure 11 is a face view of Figure 10; and 80

Figure 12 is an end view of Figure 10.

The form of block shown in Figures 1 and 2 is provided with the face portion 13, the top flange 14, bottom flange 15, and upright flanges 16. As shown in Figure 1, these 85 blocks are assembled in the wall in such manner that the flanges 14 and 15 are reversed in adjacent blocks. The flanges 15 are of greater width than the flanges 14 and the flanges 15 overlap in adjacent courses in the 90 wall, thus completely bonding the two wall faces and dividing the air space into completely closed sections.

As shown in Figure 1, the wall is supported upon a floor 16' and foundation 17. 95 The special face blocks 18 may be provided at the floor level.

The block in Figures 3 to 5 is provided with the face portion 19, lateral flange 20, and vertical flanges 21. These blocks as 100 shown are assembled in a manner generally similar to that of Figure 1. The flanges 20 are oppositely faced and overlap in adjacent courses. The vertical flanges 21 are bonded to the flanges 20 of adjacent blocks 105 and thus add to the stability and strength of the wall.

In the form of the construction shown in Figures 6 to 9, the block is provided with similar upper and lower flanges 22, these 110 flanges being substantially triangular in form, the triangle being an isosceles one

with its apex opposite the center of the face of the block. They are provided with central cross flanges 26 and end flanges 27. These blocks are placed in the wall as shown 5 in Figure 6, the opposite blocks in the same course being placed in break-joint relation, the apex of the flange of each block in one course thus overlapping the apex of the flange in the adjacent course. The blocks 10 may be so closely spaced, as shown in the figures, that the flanges overlap completely and form closed air spaces.

This block, as shown in Figures 7 to 9, has been provided with a circumferential 15 groove 23. This groove is continued around the periphery and is adapted to receive reinforcing rods to aid in bonding the wall together. If such rods are not used, the groove aids the mortar in bonding the blocks.

20 In Figures 10 to 12 a block similar in outward design to that of Figures 6 to 9 has been shown. This block, however, is provided with an outer face 24 which is composed of insulating material such as 25 cinder concrete. This layer of material is placed in the mold at the same time with the rest of the block and is formed integrally therewith. This block, further, has placed in it a reinforcing mesh 25 preferably formed of steel wire or light steel rods. The ends of the mesh are turned into the end flanges 12, as shown in Figure 10, to aid in strengthening these flanges and in bonding the reinforcement in the block.

30 This reinforcement greatly increases the strength of the block and permits the use of a block with webs of a smaller thickness than is possible without the reinforcement.

35 All of the forms of blocks shown have 40 the common feature that with them double-face walls integrally bonded and provided with closed air spaces may be formed. No special bonding blocks are required and

the body of the wall structure is formed of blocks of a single type. This greatly facilitates the production of blocks and the construction of the wall. 45

I claim:

1. A building block having a face portion and bonding flanges extending therefrom and adapted to bond oppositely faced blocks in adjacent courses, certain of the flanges having substantially the shape of an isosceles triangle, the apex being opposite the center of the face portion of the block, and the base of the triangle extending the full length of the block. 50

2. A building block having a face portion and bonding flanges extending therefrom and adapted to bond oppositely faced blocks in adjacent courses, certain of the bonding flanges being triangular in shape, the remaining flanges being comprehended within the contour of said triangular flanges. 60

3. In a wall construction, building blocks 65 having face portions and flanges extending therefrom, portions of the flanges being of greater lateral extent than other portions, the blocks being oppositely faced in the wall in such manner that flange portions of 70 greater extent in each course overlap flange portions of blocks in adjacent courses.

4. In a wall construction, building blocks having face portions and flanges extending therefrom, the blocks being disposed in the 75 wall with their flanges extending inwardly, the flanges upon blocks of one course overlapping flanges of oppositely faced blocks in adjacent courses, the overlapping flanges having continuous contact and means joining the flanges whereby separated, longitudinally extending air spaces are formed. 80

Signed at Duluth, Minnesota, this fifth day of January, 1921.

ARTHUR G. HATCH.
